IRVING V. COLE, OF NEWARK, NEW JERSEY

PANEL BOARD STRUCTURE

Application filed August 8, 1928. Serial No. 298,232.

This invention relates to panel board structures, more particularly to structures wherein a plurality of circuits are attached to a single set of bus bars.

It has long been desirable to have a panel board structure having a number of circuits thereon and so constructed as to allow ready removal of some of the circuits for replacement by others of different current carrying capacity. Occasion often arises after a panel board has been installed, for not only changing the circuits but adding new circuits. Attempts have been made to construct boards having such characteristics but, heretofore, there has not been produced a structure which was capable of meeting the requirements of the trade in all the desirable particulars.

My invention solves the problems presented in structures of this character, it being among the objects of my invention to provide a panel board which eliminates the necessity of using a heavy slate or marble panel thus effecting a great economy, and at the same time making the structure much lighter.

It is also among the objects of my invention to provide a structure which is relatively inexpensive to build and in which the several units are accessible for replacement without delay, without the necessity for expert workmen and without the use of special tools.

It is a still further object of my invention to provide a structure in which the current carrying units may be easily changed for more or less units of lesser or greater capacity, and also a structure in which the capacity may be increased at will by the insertion of additional units.

The practice of my invention is illustrated in the accompanying drawing in the several figures of which similar reference characters indicate similar parts, and in which

Figure 1 is a plan view of a panel board structure made in accordance with my invention;

Figure 2 is a cross-sectional view thereof taken along the line 2-2 of Figure 1, and

Figure 3 is an enlarged cross-sectional view thereof taken along the line 3-3 of Figure 1.

The structure includes a panel 1 of artificial insulating material, such as molded ebony

asbestos or other well-known products of this character. The thickness of this panel is usually much less than the thickness of slate previously used in panel board structures of the same capacity, is very much lighter, and less expensive. The panel 1 is usually mounted in a case not shown, and is provided with insulating end pieces 2 and 3, the piece 3 having a slot 4 therein to accommodate the conductors (not shown) which are secured to the bus bars. A series of three bus bars 5, 6 and 7 are placed centrally of the panel 1, each of said bars consisting of two bars 8 having a slot or space 9 therebetween. The ends of bars 8 are held together by members 10 and bolts 11. To one end of the bus bars 5, 6 and 7 are secured cable holders 12. The bus bars are held in their proper relative positions by insulating members 13 and 14, and bolts 15 passing thru slots 9, and members 13 and 14.

Insulating bases 16 of molded material such as ebony asbestos, or other insulating compositions obtainable on the market, have three grooves therein, into which are secured current carrying conductors 17, 18 and 19 of sufficient length to reach bus bars 5, 6 and 7, respectively. The conductors are secured thereto by bolts 20 and washers 21, the bolts passing through slots 9. The bases 16 are provided with fuse gaps 22 and cable holders 23. A block or strip 24 of insulating material fits into a groove in each of the bases 16, one end thereof being held under insulating strips 25, which are secured at their ends to pieces 2 and 3. The opposite end of block 24 is held under one of the bus bars. A screw 26 having a nut 27 thereon passes through block 24 and bears upon plate 28 in base 16, firmly wedging said base in place.

Circuits may be formed on opposite sides of the bus bars with the use of the same conductors by providing conductors 17, 18 and 19 which are secured to bases 16 on opposite sides of the bus bars, said conductors being secured at intermediate points to the bus bars by bolts 20 and washers 21.

Single phase circuits may be formed either on one side or on both sides of the bus bars by using bases 16 having only two grooves for reception of conductors 29 and 30, which

are secured as described above. Switches 31 may be provided in some or all of the circuits. Additional space 32 is provided for additional circuits as required.

5 A panel board structure of this kind may include circuits of single phase or multiple phase, switches may be provided and other elements may be substituted for the fuses therein, all as is well-known in the art. One 10 of the highly desirable features of the construction is in the ease with which any circuit may be removed without disturbing any other circuit, by merely loosening screw 26, removing block 24, removing the proper bolts 15 20 and taking out the proper base 16. This may be replaced by one or more circuits of different size or character, which renders the structure exceptionally flexible. For example, two 200 ampere circuits (or units) may 20 be removed and three 60 ampere units may be mounted in their place, and the only tool necessary to use is a screw driver.

Because I mount each circuit or unit upon 25 an insulating base which, in turn, is mounted on the panel, I obtain a high order of insulation with a relatively small thickness and weight of panel. By the provision of space 32 on the panel I allow for future expansion by the addition of circuits as the necessity 30 arises. The individual circuits are held in place by bolts fitting into slots in the bus bars and by a block which clamps the molded base to the panel, which allows of the ready rearrangement and the moving of circuits in a 35 large number of positions. Each circuit occupies no more room than on a slate panel.

Although I have described my invention setting forth a single specific embodiment thereof, my invention is not limited to the 40 details shown and described. For example, the drawing shows a structure in which circuits are attached on both sides of the bus bars, but I may arrange the bus bars on one side of the panel and attach circuits to only 45 one side of the bus bars. As shown, the bus bars carry multiphase alternating current but I may provide single phase or even direct current. The specific means for fastening parts together and other details may be varied 50 within the spirit of my invention, the scope of which is defined in the claims appended hereto.

By the term "wedge" or "wedging" used 55 in the claims I mean a friction fit sufficient to hold the parts together so that there is no relative movement thereof in normal functioning of the apparatus. By the term "clamping" I mean the securing of the parts 60 together, as current-carrying members to bus bars, by clamping means which do not include devices, as screws or bolts, which pass through substantially circular openings in the bus bars. In this connection the slots 9 65 are not to be considered as openings.

What I claim is:

1. A panel board structure comprising a panel of artificial insulating material, bus bars mounted thereon, current carrying members attached to said bus bars and mounted on an insulating base, slots in said bus bars and bolts for securing said members passing through said slots. 70

2. A panel board structure comprising a panel of insulating material, bus bars mounted thereon, current carrying members mounted on an insulating base, slots in said bus bars and means for securing said members in said slots. 75

In testimony whereof, I have hereunto subscribed my name this 2 day of August 1928.

IRVING V. COLE.
